UNITED STATES PATENT OFFICE.

HENRY C. WISSMAN, OF YOUNGSTOWN, OHIO, ASSIGNOR TO UNDERWOOD TYPEWRITER COMPANY, OF NEW YORK, N. Y., A CORPORATION OF DELAWARE.

TYPE-WRITING MACHINE.

1,148,562.

Specification of Letters Patent.

Patented Aug. 3, 1915.

Application filed December 2, 1913. Serial No. 804,136.

To all whom it may concern:

Be it known that I, HENRY C. WISSMAN, a citizen of the United States, residing in Youngstown, in the county of Mahoning and State of Ohio, have invented certain new and useful Improvements in Type-Writing Machines, of which the following is a specification.

This invention relates to typewriting machines, and particularly to machines of that class in which work-sheets for loose-leaf ledger work or other bookkeeping purposes are collated upon a board which extends upwardly and rearwardly from the carriage of the typewriter, the sheets usually having regularly spaced perforations in their side margins, whereby they engage studs running along the sides of the sheet board, said studs being connected to carry 10 the sheets around the platen after the sheets are collated, and to hold the sheets in proper 15 relationship as they travel through the machine.

In using this class of machine, the work 20 sheets are sometimes so large that it becomes necessary to make the collating board and its support much too extensive for the capacity of the typewriter.

The principal object of my improvements 25 is to overcome this difficulty.

I connect the lower end of the sheet-collating board and its frame to the typewriter carriage, so as to travel therewith, and also provide an independent support 30 for the upper end of said frame, said independent support comprising a slide or carrier and a track upon which it may move, the track being parallel with the rails along 35 which the paper carriage of the typewriter usually travels.

Other features and advantages will hereinafter appear.

In the accompanying drawings, Figure 1 is a perspective view of my improvements 40 applied to an Underwood front-strike typewriting machine. Fig. 2 is a sectional side elevation of the improvement. Fig. 3 is a sectional front elevation to show the attachment of the sheet-supporting board to the 45 paper carriage of the typewriter.

Said Underwood typewriting machine 50 usually comprises a carriage 1 running on front and rear rails (the latter shown at 3), and having a platen 4, upon the front side of 55 which strike type bars 5. The carriage is

usually propelled by a driving spring under the control of a letter-feeding mechanism operated by the type-keys, but it is not believed necessary to illustrate these parts.

From the rear of the platen extends upwardly and rearwardly a sheet-collating board 6, whose lower end 7 may terminate above the platen at the rear thereof. This board is supported upon cross bars 8, which at their opposite ends are bent down at 9 and secured to a pair of upwardly and rearwardly inclined rods 10, thus forming a frame; the rods being secured at their lower ends by screws 11 to plates or brackets 11^a provided upon the ends of the typewriter 15 carriage, whereby the frame is partly supported and is also caused to travel with the carriage.

The work-sheets may be laid upon a broad belt 13, which may be endless and at 20 its lower end may be looped around the platen 4. Its upper end may run over a roll 14; said belt carrying studs 15 at each 25 of its side edges, upon which to impale or collate the work-sheets. The upper end of 30 the board 6 terminates just below the roll 14. By revolving the platen, the sheet-carrying belt 13 may be advanced or retracted.

It is usual to arrange the sheets upon the 35 studs, and then to advance the sheets upwardly, the sheets then turning with the belt around the roll 14, and then being carried down around the under side of the board with the belt, and thence under the platen and up in front thereof to printing 40 position. As the sheets first travel up with the belt 13 their leading edges run under the forward edge of a guiding apron 17, which curves over the top of the roll, and is prolonged at 19 to extend down behind the rear 45 reach 20 of the belt, preferably terminating just in front of the paper-shelf 20^a, which extends down around the under side of the platen and up in front of the same as at 21. The belt may be of flexible material suitable 50 for carrying the sheets and for affording a suitable printing surface or backing for the sheets in conjunction with the platen 4.

The frame comprising the members 6, 8 and 10 is further supported upon a supplemental carriage 22, which may be in the form of a bar having upper and lower grooves 23 to receive balls 24 running in grooved tracks 25; the latter carried upon arms 26 which are secured at 27 to the right 55 105 110

and left-hand ends of the rear portion of the typewriter frame work 28. Opposite supports 29 extend up from said carriage and are secured at 30 to the rods 10; said 5 supports 29 being far enough apart to permit the belt 13 and the work-sheets to pass between them. Thus it will be seen that the sheet-collating board and its appurtenances, although very much over-size in respect to 10 the typewriter carriage, are still firmly supported and freely movable, and do not unduly retard the letter-feeding movements of the typewriter carriage. This additional support for the collating board may be arranged 15 high above the typewriter carriage and near the top of the collating board, as shown, so that the board structure, which is of light construction, is well supported at its upper part, which would be most liable 20 to yield if unsupported.

The rods 10 may be further connected at their upper ends by a cross bar 30^a, rigidly secured by means of nuts 31; and the paper-guiding apron 17 may be fixed to brackets 32 25 secured on the opposite ends of said bar. The brackets may be connected by a stiffening rod 33, which may also serve as a convenient support upon which to hang carbon sheets while manipulating the work sheets 30 on the collating board.

Variations may be resorted to within the scope of the invention, and portions of the improvements may be used without others.

Having thus described my invention, I 35 claim:

1. The combination of a carriage having a revolute platen, a sheet-collating board extending upwardly and rearwardly from the platen, a frame upon which said collating 40 board is carried, means associated with said collating board for carrying collated sheets to the platen and around the same, a supplemental carriage, tracks therefor, supports on the main framework of the machine 45 for said tracks, and means supporting the upper portion of said collating board on said supplemental carriage; the lower portion of said sheet-collating board being connected to said platen carriage.

50 2. The combination with a typewriter carriage having a revolute platen, of a sheet-collating board extending upwardly in an oblique angle from said platen and supported on said carriage, a supplemental 55 carriage upon which said sheet-collating board is partly supported, and means movable between said board and supplemental carriage for conveying from the face of said board upwardly around the upper end 60 of said board and thence downwardly and forwardly between said board and supplemental carriage to the platen, sheets collated upon said board.

65 3. The combination with a carriage and a revolute platen mounted thereon, of a col-

lating board extending backwardly from the platen, cross bars on which said board is supported, said cross bars bent down at their opposite ends, upwardly extending rods to which the opposite ends of the cross 70 bars are secured to form a frame, means for securing said rods at their lower ends to said carriage, a supplemental carriage for said board, and means for guiding said supplemental carriage. 75

4. The combination with a typewriter comprising a carriage and a revolute platen mounted thereon, of a collating board extending backwardly from the platen, cross bars on which said board is 80 supported, said cross bars bent down at their opposite ends, upwardly extending rods to which the opposite ends of the cross bars are secured to form a frame, means for securing said rods at their lower ends to said 85 carriage, a supplemental carriage for said board, means for guiding said supplemental carriage, said guiding means comprising a track, and a support extending from the frame-work of the typewriter to said track. 90

5. The combination with a carriage and a revolute platen mounted thereon, of a collating board extending backwardly from the platen, cross bars on which said board is supported, said cross bars bent down at 95 their opposite ends, upwardly extending rods to which the opposite ends of the cross bars are secured to form a frame, means for securing said rods at their lower ends to said carriage, a supplemental carriage for 100 said board, means for guiding said supplemental carriage, and means at opposite sides of said frame to connect the latter to said supplemental carriage; said connecting means being sufficiently spaced to permit 105 the passage of the work-sheets therebetween.

6. The combination of a machine comprising a carriage having a revolute platen, a sheet-collating board extending 110 upwardly and rearwardly from the platen, a frame upon which said collating board is carried, a supplemental carriage, tracks therefor, supports on the main framework 115 of the machine for said tracks, means supporting the upper portion of said collating board on said supplemental carriage; the lower portion of said sheet-collating board being connected to said platen carriage, a broad endless belt reaching around the 120 platen and running over an idle roll opposite to the platen, and studs upon said belt to catch perforations in the side edges of the work-sheets, said belt running over said collating board. 125

7. The combination of a carriage having a revolute platen, a sheet-collating board extending upwardly and rearwardly from the platen, a frame upon which said collating board is carried, a supplemental car- 130

- riage, tracks therefor, supports on the main framework of the machine for said tracks, means supporting the upper portion of said collating board on said supplemental carriage; the lower portion of said sheet-collating board being connected to said platen carriage, a broad endless belt reaching around the end of the platen and running over an idle roll opposite to the platen, 5 studs upon said belt to catch perforations in the side edges of the work-sheets, said belt running over said collating board, a guiding apron curving over the top of said roll and extending down in rear of the rear 10 reach of the belt, and means extending forwardly from the lower portion of said guiding apron and around the under side of the platen to guide the work-sheets toward the printing line.
- 15 8. The combination of a carriage having a revolute platen, a sheet-collating board extending upwardly and rearwardly from the platen, a frame upon which said collating board is carried, means associated with 20 said collating board for carrying collated sheets to the platen and around the same, a supplemental carriage, tracks therefor, supports on the main framework of the machine for said tracks, and means supporting 25 the upper portion of said collating board frame on said supplemental carriage; the lower portion of said frame being connected to said platen carriage.
- 30 9. The combination of a carriage having a revolute platen, a sheet-collating board extending upwardly from the platen, a frame upon which said collating board is carried, means associated with said collating board for carrying collated sheets to 35 the platen and around the same, brackets at the upper end of the frame to carry a paper apron, and a stiffening rod connecting said brackets and serving as a support for carbon sheets.
- 40 10. The combination with a typewriter carriage having a revolute platen, of a sheet-collating board extending upwardly in an oblique angle from said platen and partly supported on said carriage, a supplemental carriage upon which said sheet-collating board is partly supported, and an endless conveyer movable lengthwise around said board to introduce collated sheets to 45 the platen.
- 50 11. The combination with a typewriter carriage having a revolute platen, of a sheet-collating board extending from said platen and partly supported on said carriage, a supplemental carriage upon which said collating board is partly supported, a track therefor, and means movable between said board and track for conveying to the platen sheets collated upon said board.
- 55 12. The combination with a typewriter carriage having a revolute platen, of a 60 sheet-collating board extending rearwardly from said platen and partly supported on said supplemental carriage, a supplemental carriage beneath said collating board and upon which said board is partly supported, a track therefor, and an endless conveyer movable lengthwise around said board to introduce collated sheets to the platen, said conveyer comprising means to carry said sheets from the face of said board around the rear end of the board and thence forwardly between the said board and supplemental carriage to the platen.
- 65 13. The combination with a typewriting machine comprising a carriage and a revolute platen thereon, of a sheet-collating board extending upwardly and rearwardly from the platen, a frame upon which said collating board is carried, a supplemental carriage behind said board, a track for said supplemental carriage, supports on the main framework of the machine for said track, means supporting the upper portion of said collating board and frame upon said supplemental carriage, said board and supplemental carriage being spaced apart for the passage of work-sheets therebetween, the lower portion of said board being connected to the said platen carriage, and means for conveying work-sheets collated upon the face of said board upwardly and rearwardly past the upper end of said board, and thence downwardly and forwardly between said board and the supplemental carriage and to the platen.
- 70 14. The combination with a typewriting machine comprising a carriage and a roller platen thereon, of a sheet-collating board extending upwardly and rearwardly from the platen, a frame for said board, said frame supported at its lower end on said carriage, a supplemental carriage located behind said board and adjacent the upper end thereof, said supplemental carriage connected to and supporting the upper portion of said frame but spaced from said board to permit the passage of work-sheets between the board and said supplemental carriage, a track parallel with the platen on which said supplemental carriage runs, means on the framework of the machine to support said track, a guide roller in said frame at the upper end of said board, and an endless conveyer forming a means for guiding and conveying work-sheets from the front face of the collating board around said guide roller, and thence forwardly between said board and the supplemental carriage and to the platen.
- 75 15. The combination with a typewriting machine comprising a carriage and a roller platen thereon, of a frame extending upwardly and rearwardly from the platen, a supplemental carriage, said frame partly supported by the platen carriage and partly

by said supplemental carriage, means on the framework of the machine to support said supplemental carriage, a guiding roller mounted on the upper end of said frame, 5 and work-sheet-carrying means for carrying work-sheets around said guiding roller and downwardly and forwardly from said roller between the supplemental carriage and said frame to the platen.

HENRY C. WISSMAN.
